MECHANISM FOR NUMERICALLY GROUPING
BOOKLETS AND THE LIKECecil Joseph Sadler, Rose Bay, near Sydney,
New South Wales, Australia

Application August 8, 1950, Serial No. 178,190

1 Claim. (Cl. 93—93)

1. This invention relates to improved mechanism adapted for use for example in the printing industry for numerically grouping booklets and the like.

It is well known in the printing industry that after publications have been printed, collated, stitched and trimmed, they are normally transported to counting and packing tables or rooms and it is well known that final counting often has to be done manually. For example, in one well known cycle of operations in the printing industry, the various sections required for each copy of a publication are collated and fed to a stitching machine and after stitching, the various copies are automatically transferred to a trimming machine and imperfect copies are ejected automatically by the machine itself. After trimming, the copies are ejected from the trimming machine on to a conveyor or "flyer" for counting and packing, and it will be appreciated that in normal printing practice, as imperfect copies are ejected after stitching but before trimming (the final operation), the number of copies reaching the flyer is not always identical with the number of operating strokes of the trimming machine, so that any known counting device registering from the operating strokes of the trimming machine, would not be an accurate record of the number of copies delivered to the flyer. Also, when copies are delivered to the flyer in an unbroken sequence, the necessity for hand counting becomes obvious if such copies are to be packed for delivery in predetermined quantities such as 12, 20, 25, 50, or the like.

An object of the present invention is to provide improved mechanism for numerical grouping which will act upon articles delivered to a conveyor after all mechanical operations thereon have been completed, whereby subsequent hand counting of said articles prior to packing, is eliminated.

A further object of the present invention is to provide improved mechanism for numerical grouping which is adapted to operate in conjunction with a machine performing the final operation on articles to be delivered to a conveyor, whereby said articles are grouped in predetermined quantities.

The present invention will be described with relation to a guillotine or trimming machine performing the final operation on individual copies of publications hereinafter referred to as booklets, delivered thereto after stitching, from which said booklets are ejected on to a conveyor or flyer for delivery to a packing bench or room for example,

but it will be appreciated that a device according to the present invention need not be restricted to use on printed publications only, but may be adapted for use in other spheres.

2. According to the present invention the device is mounted upon the framework of a newspaper trimming machine. The device has a feeler slidably mounted thereon which is adapted to engage each booklet as it is carried along the bed of the trimming machine after having been trimmed but prior to being ejected on to the flyer, and for every stroke of the trimming machine and consequently for every trimmed booklet that is advanced by the trimming machine to a position beneath the feeler, a ratchet wheel mounted in the device is rotated through a distance of one tooth, but if for some reason, such as by rejection of imperfect booklets prior to trimming, a booklet or sequence of booklets is not advanced to a position beneath the feeler, said feeler will drop by gravity to its full extent and remove a pawl from engagement with the said ratchet wheel.

The operation and action of the feeler, and ratchet wheel as described is inter-operatively connected with the operation of a displacement arm which projects downwardly and outwardly from the device and which is adapted, when the ratchet wheel has been turned through 360 degrees in the manner described, to be swung inwardly over the flyer into the path of the particular booklet being ejected from the bed of the trimming machine at that particular moment, whereby said booklet is forced out of alignment with the copies thereof previously ejected from the trimming machine.

Thus it will be apparent that if the ratchet wheel has twenty-five teeth, for example, every twenty-fifth booklet delivered from the trimming machine will be out of alignment with the remaining twenty-four and subsequent counting thereof is unnecessary, and should a break occur in the sequence of delivery of said booklets to the trimming machine, the operation of the displacement arm is temporarily halted.

The device, as stated, is driven from the operating mechanism of the trimming machine and has incorporated therein the necessary gears, ratchets, pawls, cams, stops and the like to permit the said device to be operated in the manner described and further, should some heavy or large object be unexpectedly advanced into the path of the feeler, the stem thereof is provided with a knee or hinge joint whereby said feeler is raised away from the said object without fear of damage thereto.

In order that the invention may be more readily understood, reference will now be made to the accompanying drawings, wherein:

Figure 1 is a perspective view of numerical grouping mechanism according to the present invention, illustrating the disposition of said mechanism and the frame thereof with respect to a known trimming machine partly in broken lines and a known flyer associated with said trimming machine.

Figure 2 is an elevational view, with portion of the frame and portion of the displacement means removed, illustrating the mechanism according to the present invention in greater detail.

Figure 3 is a plan view of mechanism according to the present invention.

Figure 4 is an expanded perspective detail view of mechanism according to the present invention, the frame portion of the displacement means and portion of the feeler means being removed, and with various shafts broken away to more clearly illustrate the invention.

Figure 5 is a detail perspective view of portion of the booklet displacement means according to the present invention.

Figure 6 is a detail perspective view of the secondary cam according to the present invention, illustrating one disposition of the various components associated therewith.

Figure 7 is a detail elevational view of the secondary cam illustrated in Figure 6, showing the means for rotating said secondary cam.

Figure 8 is a detail perspective view of the main cam according to the present invention, one of the flanges thereof being removed to more clearly illustrate the disposition of the pawl control lever with relation thereto.

Figure 9 is a detail perspective view of the ratchet wheel, feeding pawl therefor and portion of the pawl control lever according to the present invention.

Figure 10 is a diagrammatic elevational view according to the present invention of the secondary cam, the main cam, portion of the ratchet wheel, the feeding pawl therefor, the pawl control lever and the slotted driving arm, illustrating the disposition of these various components when said slotted driving arm has been fully raised at the completion of the "up" stroke of the trimming machine.

Figures 11, 12 and 13 illustrate the respective positions of the components seen in Figure 10 when the trimming machine and hence the slotted driving arm, are in the positions of half-way down, fully down, and half-way up respectively.

According to the present invention, the frame 10 of the device is mounted upon a trimming machine of known construction capable of receiving magazines, papers, booklets and the like, henceforth referred to as booklets 9, portion 11 of said trimming machine and the moving table 12 thereof being illustrated in Figure 1, and a conveyor or "flyer" 13, above which are diagrammatically illustrated detention rollers 14 also of known construction, is illustrated in this figure, and it will also be appreciated that the known trimming machine has an arm 15 which reciprocates therewith and is utilized as power means for the present invention.

Referring to the present invention in greater detail, the frame 10 is provided with bearings to receive a ratchet shaft 16, a driving shaft 17 and a camshaft 18; the said ratchet shaft 16 in the present instance has a 25 tooth ratchet wheel 19

mounted thereon as the device is designed to indicate when groups of 25 booklets have passed from the trimming machine to the flyer 13 as will be explained in greater detail. Over-running of the said ratchet wheel 19 is prevented by means of a pinion 20 which is mounted upon said shaft 16 and is engaged by a pair of pawls 21, which latter are freely pivoted with respect to the frame 10 and are urged together by means of a spring 22, see Figures 2 and 4.

A twin membered cam secured to the ratchet shaft 16, as seen in Figures 2, 3 and 4, has a raised portion 23 on one of its members 24 and diametrically opposite which, but on the companion member 25, is a recess 26 corresponding to the said raised cam portion 23, see Figure 4, the purpose of which will be explained hereafter.

Referring again to the driving shaft 17, this has a slotted lever 27 secured thereto outside the frame 10 and adapted to be freely coupled to the said driving arm 15, for instance by a roller 28 of known construction, engaging the slot 29 in said lever 27. The said shaft 17 has a quadrant 30 mounted thereon for imparting movement to a pinion 31 secured to the camshaft 18, the said shaft 17 having a pair of lugs 32 secured thereto, between which a ratchet feeding pawl 33 is pivotally mounted; the said pawl 33 is seen in greater detail in Figure 9 and has pressure applied thereto by means of a roller 34 which is mounted upon a pair of arms 35 carried upon a shaft 36 which is mounted in the frame 10 of the device, see Figures 2 and 4; said shaft 36 also has pivoted thereto a ratchet detent 37, flexible pressure being applied to the roller 34 and the detent 37 by means of a spring 38.

Reverting to the camshaft 18, which as stated above, has a pinion 31 mounted thereon, this shaft 18 also has mounted thereon a cam 39, see Figures 4 and 7, having external flanges 40, one of which has been removed in Figure 8 to facilitate the description. The said shaft 18 has loosely mounted thereon a secondary feed cam 41 see Figure 6, and which has an abutment 42 formed in a track 43 therein, the respective faces 44, 45 of said abutment 42 being adapted to be engaged by a pin 46 carried by the shaft 18 in lost motion manner; the said secondary cam 41 is provided with a slot 47 and peripheral notches 48, 49 which latter are adapted to be engaged by pawls 50, 51 respectively, pivotally mounted with respect to the frame 10 and urged together by means of a spring 52, the said pawls 50 and 51 serving to prevent over-running of the said secondary cam 41 when the shaft 18 comes to rest.

The said ratchet feeding pawl 33, see Figures 4 and 9, which is the only means of imparting rotation to the ratchet shaft 16, is adapted to be raised and lowered out of and into engagement with the ratchet teeth, by a control lever 53, see Figures 4 and 8.

The said control lever 53 is mounted upon a shaft 54 which is pivoted in the frame 10 and rests upon the main cam 39 between the flanges 40 and has a transverse extension 55 having a foot 56 adapted to extend into the slot 47 of the secondary feed cam 41, see Figures 4 and 6. The outer end of the control lever 53 has sliding connection with a feeler rod formed in two parts 57 and 58 connected by a resilient coupling 59 and having a feeler 60 see Figure 1, disposed in the path of the moving booklets 9, the said connection between said control lever 53 and said feeler rod 57 being effected by means of a roller swivel 61; said feeler rod 57 being freely movable ver-

tically in suitable bearings 62 secured to the frame 10.

Reverting now to the twin cam member 24, 25, this is secured to the shaft 16 in such manner that the raised portion 23 thereof coincides with, for example, the 25th tooth on the ratchet wheel 19 for a purpose to be explained later. The periphery of the cam member 24 is engaged by the lower finger 63 of a bifurcated copy displacement lever 64 and the periphery of the companion cam member 25 is engaged by the upper finger 65 of the bifurcated lever 64, the said bifurcated lever 64 is pivotally mounted on a stub axle 66 having a nut 67 and extending from the frame 10, see Figure 3.

The outer end of the bifurcated lever 64 has a slotted extension 68 see Figures 4 and 5, which engages a roller 69 on a pin 70 extending from a displacement shaft 71 which is partly rotatable in a bearing 72 carried by the frame 10; said displacement shaft 71 has a displacement arm 73 secured thereto, upon the lower end of which is a displacement member 74 diagonally disposed with respect to the direction of travel of the booklets 9, said displacement arm 73 and displacement member 74 being normally out of the path of the moving booklets 9 as seen in broken lines in Figure 1 until moved into the full line position by the engagement of raised cam portion 23 with finger 64.

Operation

In describing the operation of the invention, it should be explained that the trimming machine for example, to which the invention has been fitted, is one having reciprocating vertical movement and also such that its table or conveyor 12 is capable of feeding booklets 9 from right to left as seen in Figure 1, only when the said trimming machine is moving upwardly.

If now at the completion of an upward stroke immediately prior to a downward stroke of the trimming machine, and a booklet is not beneath the feeler 60, then it will be noticed that the quadrant 30 and pinion 31 have moved the main cam 39 and secondary cam 41 into the position seen in Figure 10, and the pawl control lever 53 will be raised and supported by the main cam 39. At the commencement of this down stroke the foot 56 enters slot 47 in the secondary cam 41 and allows pawl control lever 53 to raise the ratchet feeding pawl 33 clear of the teeth of the ratchet wheel 19, so that on continued movement of shaft 17, the pawl 33 rides over the ratchet teeth without rotating the ratchet wheel 19 and ratchet shaft 16. At this position the slotted lever 27 has reached the position at the bottom of its stroke as seen at Figure 12. Meanwhile the secondary cam has moved to position seen in Figure 12.

The slotted lever 27 now moves upwards and in so doing the quadrant 30 and pinion 31 move the main cam 39 and simultaneously retract the ratchet feeding pawl 33, the latter sliding over the inner end of the pawl control lever 53. The said main cam 39, at the extreme upward movement of the slotted lever 27 has raised the control lever 53 and supports the latter with the foot 56 above the slot 47 of the secondary cam 41, as seen in Figure 10. If, during this upward stroke, a booklet 9 has moved beneath the feeler 60, then on the next downward stroke of the slotted lever 27, the main cam 39 moves from beneath the control lever 53 and the feeler 60 descends upon the booklet 9 while at the same time the feeding pawl 33 advances into engage-

ment with a tooth on the ratchet wheel 19. On continuation of the said downward stroke, the main cam 39 raises the lever 53 together with the feeler 60 and the pawl 33 feeds the ratchet wheel 19 by one tooth and simultaneously with the movement of the main cam 39, the secondary cam 41 moves to position seen in Figure 12 so as to engage the foot 56 of the extension 55 of control lever 53, holding the latter raised, see Figure 12, until just before completion of the next upward stroke when the position seen in Figure 10 is again reached and the machine will continue to operate following the respective cycles referred to above depending upon whether or not a paper has been fed beneath the feeler 60 during the upward stroke.

When booklets 9 are passing beneath the feeler 60 and hence the ratchet wheel 19 is being rotated tooth by tooth in the manner described, it will be appreciated that when the tooth of said ratchet wheel 19 representing the 25th tooth thereof, has been engaged by the pawl 33 and the ratchet wheel 19 advanced by this tooth, the raised portion 23 on the member 24 of the twin cam secured to the ratchet shaft 16, will engage the raised portion on the lower finger 63 of the bifurcated lever 64 and cause said bifurcated lever 64 to pivot on its stub axle 66, see Figures 2 and 3, thus imparting movement, through the slotted extension 68 on the bifurcated lever 64, and through the roller 69 and displacement shaft 71 to the displacement arm 73, which will momentarily swing into the full line position over the flyer 13 as seen in Figure 1, and cause the displacement member 74 to lie in the path of the particular booklet 9 about to be ejected on to said flyer 13 from beneath the feeler 60. Thus the said booklet 9 so engaged, also as seen in Figure 1, then represents the 25th booklet in a group and is out of alignment with the preceding 24 or the next 24 as the case may be, and meanwhile the displacement arm 73 and displacement members have been moved to the broken line position seen in Figure 1, by the raised portion 23 of the twin cam 24 moving from beneath the lower finger 63 of the bifurcated lever 64.

It will also be appreciated that when no booklets 9 are passing beneath the feeler 60, the ratchet wheel 19 will not be rotated for the reasons previously described, nor will the twin cam 24—25 be rotated as it is also secured to the ratchet shaft 16, and therefore the displacement arm 73 will also not be operated, so that no matter how many booklets 9 are rejected prior to the trimming (the final) operation thereon, the 25th booklet delivered to the flyer 13 will always be moved out of alignment on said flyer 13 with respect to the other 24 thereof as an indication that a group of 25 for example, of booklets has been dealt with.

I claim:

In combination, mechanism for sequentially advancing booklets and other mechanism for numerically grouping booklets so advanced, said last named mechanism comprising a ratchet having a plurality of teeth equal in number to the number of booklets desired in each group, and a cam having a single tooth angularly registered with one tooth of said ratchet, said ratchet and said cam being mounted on a common shaft; booklet displacement means actuated by said cam for displacing all advanced booklets having ordinary numbers that are multiples of the number of teeth on said ratchet; a pawl for driving said ratchet, said pawl being actuated in response to

each operation of said first named mechanism; a control lever having a footed extension, said lever being connected at one end thereof to a feeler, and at the other end thereof being in contact with said pawl; an eccentric cam in contact with said control lever; and a peripherally notched cam freely mounted adjacent to said eccentric cam, said notched cam being capable of coming into contact with said extension of said lever, said notched cam being adapted to be driven in lost motion manner with respect to said eccentric cam.

CECIL JOSEPH SADLER.
